FOOD BOWL TRAY

John F. Krieger, Grafton, and Robert S. Block, Village of Bayside, Wis., assignors to Breakthru Incorporated, Milwaukee, Wis.

Filed Oct. 27, 1971, Ser. No. 193,235

Term of patent 14 years

Int. Cl. D7—99

U.S. Cl. D7—37

FIG. 1.

FIG. 2.

FIG. 3.

FIG. 1 is a top plan view of a food bowl tray, showing our new design;

FIG. 2 is a side elevational view;

FIG. 3 is an end elevational view;

The top of the food bowl tray is flat and planar and the bottom is flat and plain.

We claim:

The ornamental design for a food bowl tray, as shown and described.
